UNITED STATES PATENT OFFICE.

JOHN A. WESER, OF NEW YORK, N. Y.

PIANO.

No. 818,496.

Specification of Letters Patent.

Patented April 24, 1906.

Application filed October 6, 1905. Serial No. 281,572.

To all whom it may concern:

Be it known that I, JOHN A. WESER, a citizen of the United States, residing in the borough of Manhattan of the city of New York, in the State of New York, have invented certain new and useful Improvements in Pianos, &c., of which the following is a specification, reference being had to the accompanying drawing, forming a part hereof.

10 In automatic pianos so much room is occupied by the automatic mechanism within the case above the keyboard as to interfere with the movement of the hinged backfall unless the case is enlarged on this account.

15 It is the object of this invention to provide a folding backfall which will fold automatically as the keyboard-cover is raised, so that it will not strike any part of the automatic mechanism, although the case is of the ordinary depth.

20 The invention is illustrated in a convenient and practical embodiment thereof in the accompanying drawing, which is a view in vertical section of so much of a piano as is necessary to enable the application of the invention to be understood.

25 The case *a* and the frame *b* of the piano may be of any usual or preferred construction. Just above the piano-keys (not shown) is secured a strip *c*, to which the keyboard-cover *d* is hinged, as usual, such cover having hinged to it an extension *e*. The backfall comprises a part *f*, which is fixed rigidly to the keyboard-cover *d*, and a part *g*, 30 which is hinged, as at *h*, to the part *f*, a spring *i* being secured to the parts *f* and *g* on the inner sides thereof for the purpose of maintaining the parts *f* and *g* normally in the same plane, as shown by full lines, while 35 permitting the part *g* to fold with respect to the part *f*, as shown by dotted lines, and acting to return the part *g* to its normal relation when permitted.

40 To the case of the piano at one end or at each end, if preferred, is secured a pin or projection *k*, with which the part *g* of the backfall makes contact when the keyboard-cover *d* is turned upon its hinge to uncover the piano-keys and is thereby caused to swing 45 upon its own hinge *h* with relation to the part *f* of the backfall and to assume the position indicated by dotted lines. The contacting surface of the part *g* is provided with a notch *l* for coöperation with the pin of projection *k*, 50 so that when the keyboard-cover and the backfall are turned back into the position

indicated by dotted lines the notch *l* shall be engaged by the pin *k* and the parts thereby held from accidental disengagement, some slight pull being required to disengage the notch from the pin when the piano is to be closed. The spring *i* serves to maintain the engagement, and its tension must be overcome before disengagement is effected. As will be understood, the extension *e* is folded 55 back upon the keyboard-cover *d* and is carried with it into the piano-case, as indicated by dotted lines.

It will be observed that the folding of the backfall permits it to be turned back within 70 the piano-case without striking the automatic mechanism or any other part that may be behind it and without requiring the case to be made of unusual depth.

75 It will be understood that the terms "key-board-cover," "extension," and "backfall" are employed herein for the sake of clearness in description, although in the art the term "fallboard" is generally understood to include the front and the back fall.

80 I claim as my invention—

1. A piano having a backfall composed of two longitudinal parts, one of which, is movable with respect to the other.

2. A piano having a backfall composed of 85 two longitudinal parts, one of which is hinged upon the other, and a spring to maintain such parts in normal relation and to permit relative movement.

3. A piano having a hinged backfall composed of two longitudinal parts, one of which is hinged upon the other, a spring to maintain such parts in normal relation and to permit relative movement, and a stop to coöperate with the movable parts.

90 4. A piano having a backfall composed of two longitudinal parts, one of which is hinged upon the other, said part having a notch, a spring to maintain such parts in normal relation and to permit relative movement, and a stop to coöperate with the movable parts and engage said notch.

95 5. A piano having a keyboard-cover hinged to its support, a backfall composed of two longitudinal parts hinged together, one of said parts being fixed to the cover, and means coöperating with the hinged parts of the backfall to cause it to fold as the cover is swung upon its hinge.

100 6. A piano having a keyboard-cover hinged to its support, a backfall composed of two longitudinal parts hinged together, one of

- said parts being fixed to the cover, a spring secured to said parts to maintain them in normal relation, and a stop fixed in the path of the movable part to coöperate therewith.
- 5 7. A piano having a keyboard-cover, a backfall composed of two longitudinal parts hinged together and means whereby the backfall is folded as the keyboard-cover is raised.
- 10 8. A piano having a keyboard-cover, a backfall composed of two longitudinal parts hinged together, and means whereby the backfall is restored to normal position as the keyboard-cover is closed.
- 15 9. A piano having a keyboard-cover, a backfall composed of two longitudinal parts hinged together, means whereby the backfall is folded as the keyboard-cover is raised, and means whereby the backfall is restored to normal position as the keyboard-cover is closed.
10. A piano having a keyboard-cover hinged to its support, a backfall composed of two longitudinal parts hinged together, one of said parts being fixed to the cover and the other part having a notch in its rear face, a spring to maintain said parts in normal relation, and a stop fixed in the path of the movable part to coöperate therewith, and engage said notch.
- This specification signed and witnessed this 5th day of October, 1905.
- JOHN A. WESER.
